MANIFOLD

Application filed May 2, 1933. Serial No. 274,593.

This invention relates to internal combustion engines and has particular reference to improvements in the manifolding systems thereof.

5 In prior manifold constructions the intake and exhaust manifold have usually been constructed as independent units. In some instances the intake manifold has been positioned wholly within the exhaust manifold, 10 the purpose of this construction being to pre-heat the carburetted mixture prior to its entry into the firing chamber. It is also common practice to provide a heated riser or a hot spot on the intake manifold to give the 15 desired pre-heating.

The present invention is particularly concerned with the construction of combined or interrelated intake and exhaust manifolds and has particular reference to the construction 20 of certain of the arms or ports of the exhaust manifold as an integral structural portion of the intake manifold. In casting the intake manifold, I preferably cast integral therewith between the central delivery ports 25 a central pair of exhaust arms or ports which are connected to and from a part of the exhaust manifold. Both of these exhaust arms or ports are provided with baffles so as to prevent the direct impinging or striking of 30 the hot exhaust gases against the adjacent portion of the intake manifold. These baffles will force the exhaust gases upwardly and away from the intake manifold and toward the exhaust manifold.

35 A central chamber cast integral with the intake manifold surrounds the upper portion of the riser as well as a portion of the intake manifold at the point where the riser joins thereon. The baffles previously referred to 40 form one of the walls of this chamber and as the exhaust gases are deflected by the baffles, only such gases as will in their natural course flow into the chamber will be allowed to cause a pre-heating of the incoming carburetor fuel.

Positioned over the intake manifold is the exhaust manifold. The central portion of the exhaust manifold is provided with an opening which fits over a corresponding opening at the top of the chamber. This 50 opening in the exhaust manifold is also adapted to take the gases from the exhaust arms or ports cast with the intake manifold. Journalled within the exhaust manifold over the opening into the chamber is a valve 55 in the form of a baffle which is capable of being turned so as to cause exhaust gases from a portion of the cylinders of the internal combustion engine to flow around and toward the hot spot on the intake manifold, 60 making it possible, during cold weather, to supply sufficient additional heat to the cold mixture coming from the carburetor, to prepare this mixture for proper distribution in the intake manifold, and proper combustion 65 in the engine. The valve is provided externally of the exhaust manifold with an operating arm capable of manual control.

The invention is disclosed on the accompanying drawing: 70

Figure 1 is an elevation of the manifolds of the invention as applied to an internal combustion engine with parts broken away and shown in section.

Figure 2 is a section on the line 2-2 of 75 Figure 1.

Figure 3 is a section on the line 3-3 of Figure 1.

Figure 4 is a plan view of the central portion of the manifolds with parts broken away 80 and shown in section.

Referring to the numbered parts on the drawing, the numeral 10 indicates the manifold system as a whole, 12 is the exhaust manifold, and 14 is the intake manifold. 85 The engine to which the invention is applied may be any suitable type of internal combustion engine.

The exhaust manifold 12 is provided with a plurality of arms, or ports 16, 18, 20, 22, 90

24 and 26, while the intake manifold is provided with the plurality of arms or ports, as indicated at 28, 30, 32 and 34, the arms being provided with means to permit of their being secured to the block of the internal combustion engine.

The engine to which the invention is applied has six cylinders, each cylinder delivering into a single exhaust arm of the exhaust manifold. The intake manifold has the outermost or end arms or ports 28 and 34 and the intermediate or innermost arms or ports 30 and 32. In passing or feeding carburetted fuel from the carburetor through the manifold and manifold arms to the engine cylinders, the outermost arm 28 feeds the two cylinders at one end of the engine and the arm 34 feeds the two cylinders at the other end of the engine while each of the intermediate ports or arms 30 and 32 feeds one cylinder at the middle of the engine.

By referring to Figures 1 and 4, it will be noted that the two central exhaust arms, or ports 20 and 22 are cast or constructed integral with the intake manifold 14. Both of these ports or arms 20 and 22 are in substantially the same plane as the arms or ports of the intake manifold 14, as is seen from Figures 2 and 3. At the end of these ports or arms 20 and 22 adjacent the intake manifold 14, baffles 36 and 38 are provided to deflect the hot exhaust gases away from the hot spot 40 of the intake manifold 14.

This hot spot 40 is positioned centrally of the intake manifold at the point where the manifold joins the riser 42. Surrounding the hot spot 40 is the chamber 44 spaced from the intake manifold to allow for the circulation of the hot exhaust gases around the hot spot. At its upper portion, the chamber 40 is open as shown at 46. The purpose of the opening being later described. The baffles 36 and 38 it will be noted form one of the walls of the chamber 44.

The exhaust manifold 12 is positioned over the intake manifold 14, and has an opening 48 at its lower central portion which opening conforms to the opening 46 of the chamber 44. The purpose of these two openings is to allow for the exhaust gas from the central exhaust ports 20 and 22 to pass into the exhaust manifold, and to allow for the circulation of the exhaust gases from the exhaust manifold around the hot spot 40, as will be later described. The two manifolds have conformable seats 49 and 51 at the openings 46 and 48 and bolts 53 passing through 46 and 55 secure both manifolds together at their central portions.

Positioned within the exhaust manifold at its central portion is a valve 50 in the form of a baffle. The valve has a central stem or axle 52 journaled in bosses 54 and 56, provided on the inside portion of the exhaust manifold 12. The stem 52 extends beyond

one side of the manifold, and has attached thereto for manual operation a handle 58. One end of this handle is coiled in spring form about and has its end secured to the extension of the stem 52, as shown at 60. The opposite end of the handle operates over and is resiliently held on the notched, preferably arcuate bar 62, the purpose of notches being to hold the handle 58 in a given position. The coiled portion 60 as well as the handle 58 give a resilient or spring action to the handle 58.

In the position of the valve 50 shown in Figures 1 and 2, all of the exhaust gas from the ports 22, 24 and 26 will impinge against the valve and be thereby deflected downwardly against the hot spot 40, to cause a heating thereof and a consequent heating of the carburetted fuel passing therethrough. This position corresponds to the extreme cold weather or "winter" position of the valve.

During the summer months, or when the weather is warmer, the valve 50 will be swung at right angles to the position shown in Figures 1 and 2, or to a position corresponding to the designation "Summer" in Figure 4. In this latter position, the valve 50 will offer substantially no obstruction to the passage of exhaust gases from the arms, or ports 22, 24 and 26, so that during the warmer weather, only such gases as will in their natural course flow toward the hot spot will cause a pre-heating of the carburetted fuel.

Intermediate positions of the valve 50 will bring about intermediate degrees of heating between the two extremes.

I claim:

1. In a manifold arrangement for an internal combustion engine, comprising intake and exhaust manifolds, said intake manifold having cast integral therewith two central exhaust ports in the same general plane of the intake manifold, a heating chamber surrounding a portion of and cast integral with said intake manifold, a baffle in each of said two central ports forming a wall of said chamber and serving to prevent the direct impinging or striking of the exhaust gases on the portion of the intake manifold within the chamber, an exhaust manifold positioned over and secured to said intake manifold, means at the secured portion of said manifolds for forming communication between the interior of the exhaust manifold, the chamber and the said pair of exhaust ports, said means overlying said baffles, and means in the exhaust manifold to control the delivery of exhaust gases to said chamber.

2. In a manifold arrangement for an internal combustion engine, comprising an intake and an exhaust manifold, a plurality of ports on each manifold forming a part thereof, a part of the ports of the exhaust manifold cast or formed integral with the intake mani-

fold, the remaining ports of each manifold having no structural interrelation with each other, and means in said part of the ports to prevent the direct impinging or striking of 5 the hot exhaust gases against the intake manifold.

3. In a manifold arrangement for an internal combustion engine, comprising an intake and an exhaust manifold, a plurality of 10 ports forming a part of each manifold, a part of the ports of the intake manifold forming exhaust ports, a heating chamber in communication with the exhaust manifold formed around the intake manifold at the meeting 15 place of said part of ports with the intake manifold, and baffle means to prevent the exhaust gases from said part of the ports from impinging or striking directly against said intake manifold.

20 4. In a manifold arrangement for an internal combustion engine, comprising an intake and an exhaust manifold, a plurality of ports forming a part of each manifold, a part of the ports of the intake manifold forming 25 exhaust ports, a heating chamber in communication with the exhaust manifold formed around the intake manifold at the meeting place of said part of ports with the intake manifold, and a baffle in each port forming said part of the ports to prevent the 30 direct impinging or striking of the exhaust gases on the intake manifold.

5. In a manifold arrangement for an internal combustion engine, comprising a plurality of separately constructed but interconnected manifolds positioned in different horizontal planes, each manifold having a 35 plurality of ports for passing gases from and to the engine, a portion only of the ports of 40 one manifold constructed integrally with a second manifold.

6. In a manifold arrangement for an internal combustion engine, comprising separately constructed but interconnected intake 45 and exhaust manifolds positioned in different horizontal planes, a plurality of ports for passing gases from and to the engine forming a part of each manifold, a part of the ports of one manifold cast or formed integral with 50 the other manifold, the remaining ports of each manifold having no structural interrelation with each other.

7. In a manifold arrangement for an internal combustion engine, comprising intake 55 and exhaust manifolds positioned in different horizontal planes, a plurality of ports for passing gases from and to the engine forming a part of each manifold, a part of the ports of the intake manifold forming exhaust ports 60 only, and a heating chamber in communication with the exhaust manifold formed around the intake manifold at the meeting place of said part of ports with the intake manifold.

65 8. In a manifold arrangement for an in-

ternal combustion engine, comprising separately constructed but interconnected intake and exhaust manifolds, a plurality of ports for conducting gases to and from the engine and forming a part of each manifold, a part 70 only of the ports of the exhaust manifold cast or formed integral with the intake manifold and interconnected with the exhaust manifold to pass exhaust gas thereto, the remaining ports of each manifold having no structural interrelation with each other.

9. In a manifold arrangement for an internal combustion engine, comprising separately constructed but interconnected intake and exhaust manifolds, a plurality of ports for conducting gases to and from the engine and forming a part of each manifold, the 75 central ports only of the exhaust manifold cast or formed integral with the intake manifold and interconnected with the exhaust manifold to pass exhaust gas thereto, the remaining ports of each manifold having no structural interrelation with each other.

10. In a manifold arrangement for an internal combustion engine, comprising separately constructed but interconnected intake and exhaust manifolds, a plurality of ports for conducting gases to and from the engine and forming a part of each manifold, the 80 central ports of said exhaust manifold formed integral with said intake manifold and being juxtaposed and positioned between the central ports of the intake manifold and interconnected with the exhaust manifold to pass exhaust gas thereto, the remaining ports of each manifold having no structural interrelation with each other.

11. In a manifold arrangement for an internal combustion engine comprising, independently constructed but interconnected intake and exhaust manifolds, a plurality of ports for conducting gas to and from the engine and forming a part of each manifold, the 85 central ports of said exhaust manifold cast integral with said intake manifold and being juxtaposed and positioned between and in the same plane with the central ports of the intake manifold, the remaining ports of each manifold having no structural interrelation with each other.

12. In a manifold arrangement for an internal combustion engine, comprising independently constructed but interconnected intake and exhaust manifolds, a plurality of ports for conducting gas to and from the engine forming a part of each manifold, a part of the ports of the intake manifold forming exhaust ports only and being connected to the exhaust manifold to pass exhaust gases thereto, and a heating chamber in communication with the exhaust manifold formed around the intake manifold at the meeting place of said part of ports with the intake manifold, said chamber adapted to re- 120 125 130

- ceive exhaust gases from said part of the ports at all times.
13. In a manifold arrangement for an internal combustion engine, comprising separately constructed but interconnected intake and exhaust manifolds, a plurality of ports forming a part of each manifold, a part of the ports of the intake manifold forming exhaust ports only and being connected to the exhaust manifold to pass exhaust gas thereto, a heating chamber in communication with the exhaust manifold formed around the intake manifold at the meeting place of said part of ports with the intake manifold, and means in said exhaust manifold positively to direct exhaust gas into said chamber.
14. In a manifold arrangement for an internal combustion engine, comprising intake and exhaust manifolds, a plurality of ports for conducting gases to and from the engine and forming a part of each manifold, a part of the ports of the intake manifold forming exhaust ports only and being connected to the exhaust manifold to pass exhaust gas thereto, a heating chamber in communication with the exhaust manifold formed around the intake manifold at the meeting place of said part of ports with the intake manifold, and manually controllable means in said exhaust manifold positively to direct exhaust gases to said chamber.
15. In a manifold arrangement for an internal combustion engine, comprising intake and exhaust manifolds, a plurality of ports for conducting gases to and from the engine and forming a part of each manifold, a part of the ports of the intake manifold forming exhaust ports only and being connected to the exhaust manifold to pass exhaust gases thereto, a heating chamber in communication with the exhaust manifold formed around the intake manifold at the meeting place of said parts of ports with the intake manifold, manually controllable means in said exhaust manifold positively to direct exhaust gases to said chamber, and means for holding said first named means in a given position.
16. In a manifold arrangement for an internal combustion engine, comprising separately constructed but independent intake and exhaust manifolds, a plurality of ports for conducting gases to and from the engine forming a part of each manifold, a part of the ports of the intake manifold forming exhaust ports only and being connected to the exhaust manifold to pass exhaust gas thereto, a heating chamber in communication with the exhaust manifold formed around the intake manifold at the meeting place of said part of ports with the intake manifold, and a valve placed transversely of the exhaust manifold over said heating chamber positively to direct exhaust gases to the heating chamber.
17. In a manifold arrangement for an internal combustion engine, comprising separately constructed but interconnected intake and exhaust manifolds, a plurality of ports for conducting gases to and from the engine forming a part of each manifold, a part of the ports of the intake manifold forming exhaust ports only and being connected to the exhaust manifold to pass exhaust gas thereto, and a heating chamber in communication with the exhaust manifold formed around the intake manifold at the meeting place of said part of ports with the intake manifold, said heating chamber formed integral with the intake manifold.
18. In a manifold arrangement for an internal combustion engine, comprising separately constructed but interconnected intake and exhaust manifolds, a plurality of ports for conducting gas to and from the engine forming a part of each manifold, a part of the ports of the intake manifold forming exhaust ports only and being connected to the exhaust manifold to pass exhaust gas thereto, and a heating chamber in communication with the exhaust manifold formed around the intake manifold at the meeting place of said part of ports with the intake manifold, said exhaust manifold positioned over and secured to said intake manifold and provided with an opening at its secured portion affording communication between said exhaust manifold and said part of the ports.
19. In a manifold arrangement for an internal combustion engine, comprising separately constructed but interconnected intake and exhaust manifolds, a plurality of ports for conducting gases to and from the engine forming a part of each manifold, a part of the ports of the intake manifold forming exhaust ports only and being connected to the exhaust manifold to pass exhaust gas thereto, and a heating chamber in communication with the exhaust manifold formed around the intake manifold at the meeting place of said part of ports with the intake manifold, said exhaust manifold positioned over and secured to said intake manifold and provided with an opening at its secured portion affording communication between said exhaust manifold and said chamber and said part of the ports.
20. In a manifold arrangement for internal combustion engines, comprising separately constructed but interconnected intake and exhaust manifolds positioned in spaced horizontal planes, a plurality of ports for conducting gases to and from the engine and forming a part of each manifold, a part of the ports of the intake manifold forming exhaust ports only, said manifolds interconnected at the said part of ports to cause all the exhaust gas to enter the exhaust manifold.
21. In a manifold arrangement for inter-

nal combustion engines, comprising separately constructed but interconnected intake and exhaust manifolds positioned in spaced horizontal planes, a plurality of ports for 5 conducting gases to and from the engine and forming part of each manifold, a part of the ports of the intake manifold forming exhaust ports only, said manifolds interconnected at the said part of ports to cause all 10 the exhaust gas to enter the exhaust manifold, and a heating jacket integral with the intake manifold at said part of ports and receiving heat from the exhaust gases of said part of ports.

15 In testimony whereof I affix my signature.
